UNITED STATES PATENT OFFICE.

JAMES M. CARPENTER, OF PROVIDENCE, RHODE ISLAND.

IMPROVEMENT IN LET-OFF MECHANISMS FOR BRAIDING-MACHINES.

Specification forming part of Letters Patent No. 57,084, dated August 14, 1866.

To all whom it may concern:

Be it known that I, JAMES M. CARPENTER, of the city and county of Providence, and State of Rhode Island, have made a new and useful invention having reference to Braiding-Machines; and I do hereby declare the same to be fully described in the following specification, and represented in the accompanying drawings, of which—

Figure 1 is a side elevation, and Fig. 2 a vertical section, of a braiding-machine racer and its spool provided with my invention, which is what may be termed a "let-off mechanism," its purpose being to preserve due tension on the yarn or thread and effect the delivery of such yarn as occasion may require while the racer may be in operation.

The invention also will allow the spool to rise on its spindle or carrier-tube for the purpose of setting free the thread when caught on or by any portion of the mass wound on the spool. It frequently or sometimes happens that a thread will get so caught and that the draft on it will be in such direction that it will fail to free the thread and revolve the spool, the consequence being a breakage of the thread. My invention obviates this difficulty.

In the drawings, A denotes the racer, of which *a* is the spindle and *b* the tension-weight standard or post, the latter being formed in the usual manner with thread eyes or passages, they being disposed in it in the ordinary way.

C is the bobbin or spool, which, in this case, instead of being arranged directly on the spindle, is placed on a carrier or tube, T, which encompasses the spindle and rests on a shoulder *e*, at the lower part thereof.

This tube T should be capable of freely revolving on the spindle, and it has a small stud, *f*, extending from it into a groove, *g*, made lengthwise in the bore of the spool. The spool should be capable of rising freely on the tube, the stud and groove serving to cause the spool and tube or carrier to revolve together when the spool may be in revolution.

A cup-shaped gear, D, is also fixed on the carrier or tube T, and serves to support the lower head of the spool, which, when at its lowest position, rests on the bottom of the concavity of the gear.

The gear D has one set of teeth only, they being arranged at equal distances apart, and each having the form of a segment of a circle or a close approximation thereto, as represented in the drawings, although this form is not absolutely necessary. It is advantageous in promoting the correct action of the wheel. The said gear so made is intended to operate with the tension-weight L, which slides vertically on the post *b*.

Fig. 3 exhibits a side elevation, Fig. 4 an inner side view, and Fig. 5 a top view, of the tension-weight. Fig. 6 is a horizontal section of it and the gear.

From the lower part of the inner side of the tension-weight a dent, *h*, is projected. The weight on its inner side is also provided with a wedge-shaped stop or lip, *i*, which is formed and arranged with respect to the dent *h* in manner as represented in the drawings.

Whenever the tension-weight may be raised high enough to carry the stop-lip above the gear the latter will be free to be revolved by the draft on the thread, and will revolve until that tooth which may be next in rear of the tooth set free by the lip may bring up against the dent. On the descent of the weight, and after the dent may have been depressed below the gear, the wedge-lip, by its action against the advanced tooth, will insure a rotary movement of the wheel, which will continue until that tooth which was previously against the dent may bring up against the lip. The draft of the thread on the spool also contributes to effect such rotary motion.

The wedge-lip and the dent enable but a single series of teeth to be used on the wheel instead of two series, as employed when the lip is not wedged.

Another mode in which I have contemplated the application of the spool to the gear, and which would be an equivalent for that hereinbefore described, although not so valuable, would be to dispense with the carrier T and apply the gear directly to the spindle and have a long standard or wire projecting vertically from the gear into a corresponding hole made in the spool and parallel with its bore.

Having described my invention, what I claim, and desire to have secured to me by Letters Patent, is as follows:

1. The combination of the tube T, the stud f, and groove g, or their equivalent, with the spool, its spindle, and the let-off mechanism, or its equivalent.

2. The improved let-off mechanism, consisting of the gear with one range of teeth, and of the dent and wedge-lip applied to the spin-

dle, and the tension-weight, substantially as specified.

JAMES M. CARPENTER.
